UNITED STATES PATENT OFFICE

2,636,439

BARREL TYPE INJECTION PUMP

William H. Mashinter, Chicago, Ill., assignor of
 nineteen per cent to Margery D. McCormick
 and Alan G. McCormick, both of Chicago, Ill.

Application December 8, 1948, Serial No. 64,076

21 Claims. (Cl. 103—41)

1

This invention pertains to a fuel injection system for an engine, and particularly to a system embodying a fuel injection pump, a transfer pump for supplying fuel from a source of supply to the fuel pump, air throttling means, and fuel supply control means associated with the fuel pump and throttling means for supplying the proper ratio of combustibles (air and fuel) to the associated engine.

Fuel injectors are substantially universally employed with low-speed oil engines of the diesel or semi-diesel type as a means for introducing thereto the heavier grade of liquid fuels such as are commonly used in engines of that type. But the lighter fuels employed, the higher operating speeds, and the wider range of speeds and loads required of gasoline engines present fuel injection problems that heretofore have never been satisfactorily solved.

An object of the present invention is to provide a fuel injector particularly adapted for use with engines of the high-speed type, employing lighter grades of fuel such as gasoline.

Another object of the invention is to provide a fuel injector so organized as to produce a fully developed readily combustible fuel spray within the very minute interval of time available at high operating speeds.

Another object of the present invention is to provide a substantially leak-proof fuel injection pump.

Another object of the invention is to provide a fuel injection pump that is substantially immune to leakage producing wear.

Another object of the invention is to provide an improved diaphragm type of pump capable of withstanding high pressures over long periods of use.

Another object of the invention is to provide a mixture ratio control mechanism for injectors.

Another object of the invention is to provide automatic enriching mechanism and automatic leaning mechanism for injectors.

Another object of the invention is to provide pump mechanism so constructed and arranged that it may be used to pump solid liquid.

Another object of the invention is to provide a pump for supplying fluid under pressure and in measured quantities to means for utilizing the supplied fluid, as where fuel is sprayed into the cylinder of an engine or where other liquid, such as water, is sprayed into such cylinder for power or anti-detonating reasons.

Another object of the invention is to provide injecting means for supplying fuel to an internal

2

combustion engine which may be used with manifold or separate cylinder injection and wherein the fuel is introduced in properly atomized condition over the entire range of operation of the engine, i. e., regardless of the operating speed of the engine.

Another object of the invention is to provide an injector for supplying fuel to an internal combustion engine, wherein a balanced diaphragm is used as the fuel pumping means.

Another object of the invention is to provide injecting means wherein the amount of fluid supplied therefrom is controlled by the pressure of the fluid delivered to the injecting means.

Another object of the invention is to provide a fuel injector adapted particularly for use with engines of a high speed type, whether operating on heavy, intermediate, or light grade fuels.

Another object of the invention is to provide an injector so constructed and arranged that it is not dependent upon any particular shape of actuating cam; but shapes of cams may be resorted to as desired, to obtain a suitable variation of injector output with variations in injector speed of operation (engine speed).

Another object of the invention is to provide an injector so constructed that it will operate over a large range of supply pressures.

Another object of the invention is to provide a fuel injector so constructed and arranged that a complete degree of load-speed control is obtained by virtue of four independent controls over the amount of fuel emitted per injection, that is, (1) mechanical throttle, (2) variable supply pressure, (3) speed of injection operation, and (4) manifold pressure.

Another object of the invention is to provide an injector using a controlled balanced diaphragm form of pump means for injection operation.

Another object is to provide a fuel injector capable of effecting a more accurate control of the quantity of fuel injected throughout the entire range of engine speeds and loads.

Another object of the invention is to provide a fuel injection system wherein no special air release mechanism need be provided to eliminate accidentally entrapped air, as the system is so designed as to digest such entrapped air without damage to the operation thereof.

Another object of the invention is to provide a system wherein there are no frictionally moving parts in that portion of the fuel handling means through which the fuel passes.

Another object of the invention is to provide a

transfer pump for an injection system wherein the amount of the fuel delivered is controlled (or maintained) by a preset relief valve on the pumping fluid side which controls the pressure applied to the fuel.

Another object of the invention is to provide a transfer pump for an injection system wherein the amount of fuel supplied can automatically be preselected according to the demand.

Another object of the invention is to provide a transfer pump for an injection system wherein fuel is supplied at substantially constant pressure (substantially without pulsations).

Another object of the invention is to provide a transfer pump for an injection system wherein the driving force for the fuel is yieldable, and adjustable means (spring), which is energized by positively operable means (cam), is adapted to be driven by the engine to which the fuel is ultimately supplied, or by any other power means.

Another object of the invention is to provide a transfer pump for an injection system wherein the transfer pump embodies all the objects herein enumerated for the injection pump.

With these and various other objects in view, the invention consists of certain novel features of construction and operation as will be more fully described and particularly pointed out in the specification, drawings and claims appended hereto.

In the drawings, which illustrate embodiments of the device and wherein like reference characters are used to designate like parts—

Figure 1 is a fragmentary, sectional elevation of an internal combustion engine provided with an injection system embodying the invention;

Figure 2 is a sectional elevation through the injection pump of the system illustrated in Figure 1, the same showing in detail an injection pump assembly embodying the invention;

Figure 3 is a transverse, sectional plan view taken substantially in the plane as indicated by the line 3—3 of Figure 2;

Figure 4 is a transverse, sectional plan view taken substantially in the plane as indicated by the line 4—4 of Figure 2;

Figure 5 is a transverse, sectional plan view taken substantially in the plane as indicated by the lines 5—5 of Figures 1 and 2 and showing both the pump and air to fuel ratio control device;

Figure 6 is a transverse, sectional plan view taken substantially in the plane as indicated by the line 6—6 of Figure 2;

Figure 7 is a transverse, sectional plan view taken substantially in the plane as indicated by the line 7—7 of Figure 2;

Figure 8 is a bottom plan view of the injection pump illustrated in Figure 2;

Figure 9 is a side elevation of the plate cam for operating the pumping assemblies of the injection pump;

Figure 10 is a sectional elevation of a roller follower assembly used in the pumping assemblies;

Figure 11 is a bottom plan view of the roller follower assembly illustrated in Figure 10;

Figure 12 is a front elevation of the throttle finger of the injection pump, the same looking toward the left as viewed in Figure 2;

Figure 13 is an enlarged sectional elevation of the plunger throttle yoke of the injection pump illustrated in Figure 2;

Figure 14 is an enlarged elevation, partly in section, of a plunger for a pumping assembly of the injection pump;

Figure 15 is a top plan view of the plunger illustrated in Figure 14;

Figure 16 is an enlarged sectional elevation of a diaphragm stop member utilized in a pumping assembly, the same being taken substantially in the plane as indicated by the line 16—16 of Figure 17;

Figure 17 is a bottom plan view of the stop member illustrated in Figure 16;

Figure 18 is a transverse sectional elevation of the diaphragm assembly used in a pumping assembly;

Figure 19 is a transverse sectional elevation of the transfer pump used in the system illustrated in Figure 1, the section being taken substantially in the plane as indicated by the line 19—19 of Figure 20;

Figure 20 is a top plan view of the transfer pump illustrated in Figure 19, with the cover thereof removed;

Figure 21 is a bottom plan view of the transfer pump illustrated in Figures 19 and 20;

Figure 22 (sheet 1 of the drawings) is a fragmentary elevation of a modified form of connection between the transfer pump and source of fuel supply of the system shown in Figure 1, and

Figure 23 is a fragmentary, sectional top plan view, more or less diagrammatic, showing mechanical means for operating the injector pump and air throttle valve, the same looking down on the butterfly valve illustrated in Figure 1, the section of the pump being taken substantially in the plane as indicated by the line 5—5 of Figures 1 and 2.

Referring first of all, more particularly, to the injection system illustrated in Figure 1, the internal combustion engine 50 is provided with a certain number of cylinders, in the embodiment shown, the engine being a six cylinder one. The cylinders are each provided with reciprocating pistons, properly timed and fired, with respect to each other, and by way of example the single cylinder 52 shown in block 54 is provided with reciprocating piston 56, the engine being provided with cylinder head 58. Said head 58 is provided with a combustion chamber above each cylinder, such as combustion chamber 60 provided above cylinder 52.

Cylinder head 58 is provided with the air inlet or throttle housing 62 open at one end to the atmosphere, preferably through a suitable air cleaner (not shown), the housing being provided with throttle lever 64 connected through shaft 66 to butterfly valve 68. Movement of throttle lever 64 between the full and dotted line positions illustrated in Figure 1 determines the quantity of air supplied through the throttle housing, it being noted that valve 68 is never quite closed.

Throttle housing 62 communicates with manifold 70, connected through suitable air ports or passages to the combustion chambers, cylinder air port 72 being illustrated connecting manifold 70 to the combustion chamber 60. Flow through port 72 is controlled by valve 74 adapted to be moved between open and closed positions on seat 76, the valve stem 78 extending through a suitable guide 80 and being actuated by means such as rod and rocker arms (not shown) overhead cams or the like, the cams controlling valve 74, and similar valves to the other cylinders being operated by a suitable cam shaft (or cams) timed with respect to the operation of the pistons (56 and the like) of the engine, in the well-known manner.

Manifold 70 communicates, through port 82,

with one end of the pipe 84, the other end of said pipe being connected through port 86 (Figure 5) to the chamber 88 of air to fuel ratio control device 89. Chamber 88 is defined by cap 90 and flexible diaphragm 92 fastened between cap 90 and housing member 94. Atmosphere chamber 96 defined between diaphragm 92 and housing 94 communicating with the atmosphere through port 98. Diaphragm 92 is urged toward the left as viewed in Figure 5 by the spring 100, one end of said spring being seated on the spring seat 102 provided on the diaphragm, the opposite end of said spring being received in helical grooves 104 of adjustable spring retainer 106.

Retainer 106 is provided with threaded adjusting extension 108 provided with tool (screw driver) receiving recess 110, extension 108 being threaded to threaded retaining sleeve 112, said sleeve being suitably shouldered as at 114 to engage complementary shoulders on housing 90. A sealing retaining washer 116 is interposed between housing 90 and closure nut 118 whereby when the nut is tightly in place a sealing function occurs between sleeve 112, housing 90 and washer 116, whereby chamber 88 is closed to atmosphere thereby only having communication with manifold 70 (Figure 1).

Diaphragm 92 is provided with nut 120 (Figure 5) threadedly connected to complementary threads of pump throttle rod 122, said throttle rod extending into guide passage 124 of housing 126 provided on injection pump housing 128, the stroke of throttle rod 122 being governed by adjusting screw 128 extending into passage 124. Throttle rod 122 is connected through slot 130 to ball 132 (forming a ball and slot connection) provided on pin 134, said pin being fixed as at 136 to throttle finger collector ring 138 (Figures 2 and 5). Pin 134 carried by the collector ring, is fixed to the ring by assembling it radially outwardly of the ring and is tightly secured to the ring by abutting the shank of the pin against shoulder 140 provided on the collector ring.

The injection pump (Figures 1-18) is provided with cam drive shaft 142 shown as mounted in antifriction bearings 144 and 146 (Figures 2 and 3), said shaft being driven, preferably by the engine at a certain speed, for example at half crank shaft speed for a four stroke cycle engine and at crank shaft speed for a two stroke cycle engine. Bearing 144 is suitably mounted in the barrel housing 148 adjacent the pump base and valve housing 150, housing 148 being suitably secured as at 151 to housing 150 (Figures 2, 7 and 8). Antifriction bearing 146 is mounted in upper bearing housing 152, forming part of the pump housing and closed by closure 153 secured thereto as at 155, the inner race of said antifriction bearing 146 being mounted on journal 154 of plate cam 156, secured to shaft 142 to be rotated thereby. Cam 156 is provided with lobe 158 adapted to contact rollers 160 (Figures 2, 4 and 10) pivotally mounted as by pins 162 to arms 164 provided on each cam or roller follower assembly 166. The axes of pins 162 intersect the axis of cam drive shaft 142 to properly present rollers to the cam lobe 158 as it rotates to engage said rollers.

In the construction illustrated, the engine illustrated in Figure 1, is assumed to be a six cylinder engine. Consequently the injection pump is provided with six pumping assemblies illustrated generally in Figures 4 and 6 at 168, 170, 172, 174, 176 and 178. Inasmuch as all of the pumping assemblies are similar, a description

of only one pumping assembly, such as illustrated in Figure 2, need be made in detail.

Cam follower assembly 166 (Figures 2 and 10) is provided with a substantially cylindrical portion or skirt 180 slotted as at 182, for the purpose to be later described, and end closure 184 of the roller follower assembly is provided with spaced apertures 186. Cylindrical skirt 180 of the follower assembly is adapted to reciprocate in cylinders or bores 187 (Figures 2 and 4) provided in follower housing 188, said bores accommodating assemblies 168 to 178, inclusive, respectively, the follower assemblies being lubricated through passage 189 (Figure 2).

15 Follower housing 188 is provided with pin 190 (Figure 2) adapted to be received in slot 182 of the follower assembly 166 to prevent rotation of said follower assembly and to maintain the axes of pins 162 in the before mentioned positions, 20 housing 188 being secured to barrel housing 148 by studs 191 (Figures 2, 4 and 6), and secured to housing member 152 as by studs 193 (Figures 2, 3, 4, 5 and 23). Thus lobe 158 of cam 156 will always engage rollers 160 in proper path, for 25 while the assemblies 166 and rollers 160 may reciprocate, they cannot rotate about the axes of bores 187.

Upper spring seat 192 (Figure 2) is provided within cylindrical member 180, being seated thereon as at 194, and one end of spring 196 seats on said seat 192, the other end of said spring seating upon lower spring seat member 198, which in turn seats upon shoulder 200 formed in bores 187 of follower housing 188. Upper spring 30 seat 192 is provided with a recess 202 for the reception of the head 204 (Figures 2, 14 and 15) provided on the upper stem portion 205 (Figure 14) of metering plunger 206, lower end portion 207 of said plunger being provided with the 35 helical metering or cut-off edge or portion 208.

Collector ring 138 is provided with elongated slots 210, six in number in the embodiment shown, and in substantial radial alignment (Figure 5) with pumping assemblies 168 to 178, inclusive. 45 Throttle fingers 212 (Figures 2 and 12) are adjustably connected to collector ring 138 through slots 210, as by means of the cap screws 214 threadedly connected to complementary threads in fingers 212. Fingers 212 extend downwardly 50 of pump housing 128, fingers 212 being oscillatably mounted on spaced tracks 216 on housing 188 whereby freedom of rotation of fingers 212 (about the axis of shaft 142) is obtained. Fingers 212 are provided with shoulder 218 supported on the corresponding shoulder on the follower housing 188.

The lower end of the fingers are bifurcated as 55 at 220 (Figures 2 and 12) for receiving the ball end 222 of the plunger throttle yoke 224 (Figures 2 and 13). The yoke is provided with the circular segmental portion 226 which in turn is slotted as at 228 for embracing the flat shank portion 230 (Figures 14 and 15) of the metering plunger 206. The segmental portion 226 is supported on the upper rim of the barrel retaining nut 232 (Figure 2) and is rotatably (and horizontally as viewed in Figure 2) positioned by the circular recess 234 provided in lower spring seat 198. Thus plunger throttle yoke 224 is positioned in a horizontal plane and is permitted slidably engagement with metering plunger 206, the flat portion 230 of the plunger being long enough to permit the full allowable stroke of the plunger, rotation of yoke 224 by the associated throttle 65 finger 212 causing rotation of the plunger and

consequently a change in position of the helical edge or portion 208.

Retaining nut 232 (Figure 2) is provided with hex head 236 to facilitate the application of nut 232 into barrel housing 148, nut 232 being provided with threads 238 adapted to have threaded engagement with complementary threads provided in housing 148, nut 232 having spaced passages 239 permitting passage of liquid. Plunger 206 reciprocates in barrel 240, said barrel extending within nut 232, shoulders 242 relatively positioning the barrel and nut, and said barrel seats at its lower end on diaphragm stop member 244 (Figures 2, 16 and 17). Barrel 240 is provided with slot 246 adapted to receive one end of barrel set screw 248, whereby said barrel is fixed against rotation, and said barrel is provided with ports 250 communicating with the inside of said barrel and controlled by plunger 206 reciprocating therein.

Stop member 244 (Figures 2, 16 and 17) is provided with passage 252 which communicates with upper port 254, which in turn communicates with barrel 240 below plunger 206. Said passage 252 also communicates through ports 256 with the cavity or recess 258 (Figure 16) which is provided between wall 260 of stop member 244 and the top of resilient diaphragm 262 (Figures 2 and 18). In other words, wall 260 is disposed above or recessed within the outer rim 263 of stop member 244. Diaphragm 262 is preferably made of a flexible, resilient material which is chemically inert to petroleum products or to the product being pumped, and the hydraulic fluid, such as synthetic rubber; plastics as Teflon (tetrafluoro ethylene), methyl acrylate, or metals as 18-8 stainless steel, said diaphragm being bonded or otherwise held to a diaphragm ring 264 (Figure 18) which is of flanged construction, the lower inwardly directed flange 265 (Figure 18) being seated on a shoulder 266 (Figure 2) provided on valve housing 150 in alignment with each pumping assembly and being fixed by engagement with rim 263 of stop member 244. Flange 265 extends inwardly to a fuel cavity 268 provided in housing 150, to a point where it covers the spaced ports 270 and 272.

Inlet port 270 (Figure 2) is adapted to be supplied with fuel by means of inlet valve 274, spring 276 interposed between the valve and housing 150 urging the valve to seated position on the seat of valve seat member 278 which is held in place in valve housing 150 by nut 280. Access to nut 280 is readily had through closure screw 281 disposed in housing 150 in alignment with the adjusting nut 280. The valve stem of valve 276 is provided with flats or grooves for permitting passage of liquid past the stem and to port 270 when the valve is open, nut 280 being ported as at 282 for permitting passage of fuel to the valve. Fuel intake manifold 284 (Figures 1, 2 and 8) is provided on pump base housing 150, and is provided with inlet fitting 286 (Figures 1 and 8) and fuel outlet 288 connected respectively to lines 290 and 292 (Figure 1). Line 290 is connected to outlet 294 (Figures 19 and 21) of transfer or supply pump 296, and line 292 is a return to fuel storage tank 298 (Figure 1). With the transfer pump such as illustrated in Figures 19 to 21, inclusive, return line 292 is not always necessary, so either no outlet fitting is provided, or it is plugged up and may be used for flushing the pump under certain conditions.

Port 272 (Figure 2) communicates with outlet valve 300 seated on seat member 302 provided

in a suitable recess disposed in valve housing 150, the valve stem of valve 300 being likewise provided with flats or grooves for permitting the passage of fuel thereby, the valve being urged toward closed position by means of spring 304 interposed between said valve 300 and a suitable valve seat provided in outlet fitting 306. Fitting 306 is suitably connected to line or pipe 308 (Figure 1) which is, in turn, connected to nozzle 310 suitably secured to the engine to supply fuel into combustion chamber 60, nozzle 310 being preferably of the construction shown and described in application Serial No. 617,752, filed September 21, 1945, Mashinter and Gilbert, Spray Nozzle, now Patent No. 2,555,803. In the construction shown, there will, of course, be six outlet fittings 306 (Figure 8) from each of the pumping assemblies 168-178, each connected through its line 308 to the respective nozzle 310 of the associated cylinder.

Transfer pump 296 (Figures 1, 19, 20 and 21) is provided with the transfer pump drive shaft 312 preferably driven as by the cam shaft of the engine, the volume pumped by the pump being in excess of the fuel requirements of the system. Drive shaft 312 is provided with cams 314 and 316 and said shaft is adapted to rotate in a counterclockwise direction as viewed in Figure 19. Bell cranks 318 and 320 are oscillatably mounted on the shaft 312 disposed adjacent and parallel to shaft 312. Cams 314 and 316 and bell cranks 318 and 320 are adapted to operate a pair of similar pumping assemblies 324 and 326 (so that it is only necessary to describe one assembly) two or more pumping assemblies preferably being used to eliminate supply pulsations.

Shaft 312 is suitably journaled in, and shaft 322 is disposed in, upper housing 328 which is closed by covers 330 and 332 (Figures 19 and 20) and housing 328 is provided with lower housing 334 suitably secured to the upper housing. Housing 328 is threaded as at 336 (Figure 19) for the reception of upper spring seat 338 for the upper end of compression spring 340, the lower end of said spring being seated on spring seat 342 carried on shoulder 344 provided on plunger shank 346.

Plunger shank 346 is headed as at 348, the head contacting over substantially a line contact with antifriction member 350 disposed between head 348 and bifurcated arm 352 of bell crank 320 (and 318). The lower end or piston (or plunger) 354 of the plunger is adapted to reciprocate in bore 356 provided in lower housing 334, and communication is had from chamber 358 of upper housing 328, through passage 360, passage 362 and port 364 to chamber 366 above diaphragm stop member 368. The diaphragm stop member is held between the shoulder 370 and diaphragm ring 372 positioned on shoulder 314 of lower housing member 376 of lower housing 334.

Diaphragm stop member 368 (Figure 19) is similar to diaphragm stop member 244 (Figure 16), being provided with port 378 communicating with chamber 366, said port communicating with transverse passage 380 communicating with ports 382 and 384. Ring 372 is provided with diaphragm 386, of similar material to diaphragm 262, and is suitably held to the ring 372. Below diaphragm 386 and ring 372 a fuel cavity 388 is provided, communicating through inlet port 390 with inlet 392 (Figures 19 and 21) which is connected through inlet pipe or line 394 (Figure 1) to supply tank 298.

Intake valve retaining screw 396 (Figure 19) is secured in bore 398 of member 376, the lower end of said bore being closed by closure 400, screw 396 being provided with passage 402 therethrough, said screw forming positioning means for intake valve 404. Said valve comprises a ported valve seat and retaining member 406 and valve disk 408 urged towards closed position by means of spring 410 whereby the passage from inlet 392 to port 390 is controlled. Cavity 388 is connected through port 412 to outlet 294, said outlet communicating with bore 414 closed at its lower end by the closure 416, a ported spring seat 418 being threadedly secured within said bore said spring seat positioning the ported valve seat member 420. Said valve seat member 420 is secured between an upper shoulder or rim on spring seat member 418 and a shoulder on lower housing member 376 adjacent port 412. Valve 422 is adapted to seat on seat member 420, being urged towards closed position by means of spring 424 interposed between seat member 418 and valve 422, the valve stem being provided with flats for permitting passage of fuel from said port 412, past valve 422 and through the port of spring seat 418 to outlet 294. Outlet 294 communicates with passage 426 (Figure 21) and inlet 392 communicates with passage 428, said passages communicating with the intake and outlet valves of both pumping assemblies of transfer pump 296, and both passages being closed at one end as by plugs 430.

In order to balance the pressure on diaphragms 262 (Figure 2) and 386 (Figure 19), and to provide lubrication for the parts of barrel pump (Figure 2) and transfer pump (Figures 19, 20 and 21), barrel or injection pump hydraulic oil is placed in casing 128 (Figure 2) filling it to the level indicated at 432 (Figure 2) from the diaphragms, and transfer pump hydraulic oil is placed in transfer pump 296 filling the casing to the level 434 (Figure 19) from the diaphragms, i. e., enough oil is provided to provide an adequate splash system and insure oil being between the pistons and associated diaphragms.

In Figure 22 (Sheet 1) there is shown a modification of the return line connection shown in Figure 1. In Figure 22 return line 292 is provided with check valve 436 opening toward the source of supply 298, the valve being set to open at a pressure below that of supply pump 296 so that any air trapped between pump 296, manifold 284 and valve 436 will be eliminated.

In the operation of the system and the parts thereof illustrated in Figures 1 to 22, inclusive, it is assumed that engine 54 is a six cylinder, four stroke cycle engine, firing in the conventional manner (as 1, 5, 3, 6, 2, 4) and wherein transfer pump drive shaft 312 is conveniently operated as from the cam shaft or crank shaft of the engine, though of course it is to be understood that the transfer pump may be operated by any power driven means. The transfer pump is driven so that it supplies more fuel to the barrel pump (Figure 2) than is necessary to operate the barrel pump at maximum capacity, thus insuring that diaphragms 272 of the barrel pump never bottom, and engine 54 is always supplied with enough fuel.

Drive shaft 142 of the injection pump is conveniently driven by (four stroke cycle) engine 54 at one-half crank shaft speed as before described. Where a two stroke cycle engine is used, shaft 142 is driven at crank shaft speed. Rotation of shaft 312 in a counterclockwise direction, as

viewed in Figure 19, causes cam 316 (and cam 314) to rotate, oscillating bell crank 320 in a clockwise direction as viewed in Figure 19, lifting plunger shank 346 to compress spring 340. Upward movement of plunger 346 causes upward movement of piston 354 in the transfer pump hydraulic oil.

It will be seen that downward movement of the plunger is dependent upon spring 340, and not upon the direct drive from cam 316. Expansion of spring 340 causes downward movement of piston 354, which in turn causes the hydraulic oil between piston 354 and diaphragm 386 to flow through passengers 378, 380 and ports 382 to depress diaphragm 386 downwardly into fuel cavity 388. Any fuel in cavity 388 will be displaced, causing said fuel to flow through port 412, past valve 422, being supplied through passage 426 (Figure 21) and port 294 to line 290, through which it is supplied to the inlet 286 (Figures 1 and 8) of the injection pump.

When fuel from cavity 388 has ceased to flow past valve 422 (and when the pressure of the hydraulic oil above diaphragm 386 is relieved by piston 354 being raised) spring 424 will close said valve. Inasmuch as cams 316 and 314 are disposed 180° apart, while one piston 354 is moving downwardly on its supply stroke, the other piston is being raised. As cam 314 (or 316) is operating the bell crank 318 (or 320) to raise the associated piston 354, the other piston is being moved on its compression stroke. Upward movement of piston 354 will relieve the pressure of the transfer pump hydraulic oil on diaphragm 386, previously compressed on its supply stroke, permitting the diaphragm to return to normal position, such as illustrated in Figure 19. Upward movement of piston 354 tends to pull a vacuum, thus aiding the return of diaphragm 386 to its normal position.

Inasmuch as the fuel has been displaced from cavity 388 on the discharge stroke, upward movement or return movement of the diaphragm will tend to pull a vacuum in cavity 388, causing valve 498 to open against spring 410, and causing fuel to be drawn from tank 298 (Figure 1), through line 394, through port 392 and passage 428, past valve 498 and through port 390 into cavity 388, conditioning said cavity to supply fuel to discharge port 294 as hereinbefore described. Due to the fact that while one of the plungers 354 is performing its compression or supply stroke, the other plunger is performing its suction stroke, there will always be an abundant supply of fuel through line 290 to the transfer pump at constant pressure. Fuel which is constantly supplied to line 290 will be supplied through inlet 286 (Figures 1 and 8) to fuel intake manifold 284 (Figure 2), said manifold communicating with ports 282 of inlet valves 274 of the respective pumping assemblies.

Rotation of shaft 142 (Figure 2) will rotate cam 156 causing lobe 158 of the cam to serially engage rollers 160 of the pumping assemblies. Lobe 158 will cause downward movement of roller follower assembly 166 of the pumping assemblies one after another, causing the cam follower assembly to reciprocate in the injection pump hydraulic oil. Downward movement of cylindrical portion 180 will cause spring 196 to be compressed and after cylindrical member 189 has moved a predetermined amount in a downward direction (a few thousandths of an inch in the embodiment shown) it will engage head 204 of plunger

206 to move the plunger downwardly with assembly 166.

Downward movement of plunger 206 will cause the injection pump hydraulic oil, disposed below the lower end of the plunger, to flow downwardly through port 254, passage 252 and ports 256 to act upon the top of diaphragm 262, causing downward deflection of diaphragm 262 into cavity 268. Fuel disposed in cavity 268 will be forced through port 272, past valve 300, which has been opened against spring 304, and through line 308 to the respective injection nozzle 310 through which it is supplied to the associated combustion chamber 60.

Movement of lobe 158 to disengage roller 160, 15 of the actuated roller follower assembly, will permit spring 196 to move roller follower assembly 166 upwardly, and will also cause upper spring 192 to pick up head 204 of plunger 206 to move it upwardly to a position where it is ready for another downward stroke, in which position the before mentioned clearance is between the top of head 204 and roller follower assembly 166. As above pointed out, cam 156, in its rotation, successively engages the roller of the follower assemblies, causing downward movements of the respective pistons of the pumping assemblies supplying fuel in the proper order and selected amount to the combustion chambers of engine 54, and the return of said pistons by the respective springs 196 will cause upward movement of the pistons permitting the pump pressure of transfer pump 296 to aid in returning diaphragms 262 to their normal dwell positions wherein they are disposed such as shown in Figure 2.

Return of said diaphragms to said dwell positions tends to cause a vacuum to be formed in cavities 268 and this, aided by the pressure supplied by transfer pump 296, will cause valves 274 to be opened against springs 276 to fill said cavities 268, inasmuch as immediately upon cessation of the supply of fuel past valves 300, said valves will close. The cavities thus filled will be conditioned for the next compression or supply (to engine) stroke.

As before pointed out, if transfer pump 296 supplies more fuel to manifold 284 than is actually needed by the injector pump, said fuel will return through line 292 to the source of supply. If return line 292 is not used, no more fuel will be supplied by the transfer pump to the injector pump than is actually needed by the injector pump for it to supply the proper amount of fuel through injectors 310 to the respective combustion chambers, inasmuch as due to the construction of transfer pump 296, springs 340 (Figure 19) will only supply the amount of fuel to the injector pump that it is using.

The capacity of transfer pump 296 is preferably made large enough so that it is always capable of supplying more fuel to the injector pump than the injector pump will supply to nozzles 310, so that in the event air is trapped in the system, or the operation of the system is initiated when the injection pump is in dry condition or substantially dry condition, only a few revolutions of transfer pump shaft 312 is necessary to supply an adequate amount of fuel to the injector pump so that it can become operative to supply fuel to injectors 310 of engine 54.

In the construction illustrated in Figure 22 return line 292 is provided with check valve 436 opening toward source of supply 298, but set to open at a pressure below that of supply pump 296 so that valve 436 will open quickly and eliminate

any air trapped between transfer pump 296, manifold 284 and valve 436, thus eliminating air from being supplied to the injectors particularly upon initiation of the operation of the system.

5 Variations of the output of the engine are obtained by movement of butterfly valves 68 (Figure 1) by lever 64, which lever 64 may be connected to the conventional accelerator pedal or other actuator. In Figure 1 valve 68 is shown in full line position wherein it is nearly, but not quite closed, so that some air can be supplied to manifold 70, in which position of valve 68 engine 54 is in idling condition. In this idling condition the engine vacuum is generally between seventeen and twenty-one inches of mercury. The idling manifold vacuum acts upon diaphragm 92 (Figure 5) causing the diaphragm to move against spring 100 thereby moving throttle rod 122 toward the right as viewed in Figure 5, in 10 turn causing throttle pin 134 to move collector ring 138 in a counterclockwise direction as viewed in Figure 5.

Movement of ring 138 in a counterclockwise direction causes throttle fingers 212 (Figures 2 25 and 12) to move yoke 226 (Figures 2 and 13) to rotate the metering plunger 206. Plunger 206 is rotated to a position where the plunger has an effective stroke sufficient to supply the idling quantity of fuel to the combustion chamber. In 30 other words, the helix is so disposed that a sufficient quantity of oil is by-passed through ports 250 (Figure 2) to only retain sufficient oil below the plunger to actuate diaphragm 262 an amount necessary to supply the idling quantity of fuel.

35 (In the embodiment shown, the idling position is not the position of the minimum deflection of diaphragm 262. Actually this deflection is more than this minimum deflection. By way of example, the system herein disclosed has been 40 applied and successfully operated on a 572 cubic inch four stroke cycle, naturally aspirated, 6 cylinder engine wherein it is necessary to supply substantially 60 cubic millimeters of fuel on the idle (substantially 350 R. P. M.) and substantially 180 cubic millimeters at full throttle, and the injection pump can be controlled to supply only 4 cubic millimeters of fuel.)

In the idling position wherein the metering plunger is properly disposed, diaphragm 92 (Figure 5) is in the position where it is balanced 50 by the spring 100, inasmuch as the spring is set by adjustable spring retainer 106 (Figure 5) to the proper position wherein the vacuum multiplied by the area of diaphragm 92 is equal to the pressure or resistance of spring 100.

55 With throttle valve 68 (Figure 1) closed to the predetermined position such as illustrated in the full line position of Figure 1 setting the throttle control is effected, that is, in order to set diaphragm 92 (Figure 5) to a position to give the selected air-to-fuel ratio, an adjustment is made at nut 128, whereas spring rate of the spring 100 is adjusted by means of retainer 106 and retaining sleeve 112.

Movement of throttle lever 64 from the full 65 line position toward the dotted line position shown in Figure 1, causes valve 68 to move from its idling or nearly closed position, toward the dotted line or maximum open position. This opening of the throttle (and throttle valve 68) permits additional quantities of air to be introduced into manifold 70, thus changing the vacuum conditions in said manifold and consequently in chamber 88 (Figure 5). This change 70 is a lowering of the engine vacuum which causes

spring 100 to move diaphragm 92 toward the left as viewed in Figure 5, until the position of balance is reached. This movement causes throttle rod 122 to move toward the left as viewed in Figure 5, rotating ring 138 in a clockwise direction, which in turn moves throttle yokes 226 to rotate metering plungers 206 causing earlier registration of the helices with ports 250, thus making more of the plunger stroke effective, thereby increasing the amount of deflection of diaphragms 262. As the deflection of diaphragms 262 become greater, more fuel is supplied from cavities 268 past valves 380 to the respective injectors 319. The maximum position of ring 138, that is, the maximum amount of fuel supplied to the combustion chamber, is controlled by means of set screw 429 which controls the limit of movement of throttle rod 122 toward the left as viewed in Figure 5, thus controlling the limit of rotation of metering plungers 206.

Assuming the load to be constant, as throttle valve 68 (Figure 1) is opened, more and more fuel will be supplied through nozzle valves 319 and increased speed of rotation will be obtained by the crank shaft of engine 54.

Assuming that valve 68 is in a position in the engine above referred to, that at 2400 R. P. M. there is a 60% output, if the load is varied to decrease the engine speed, to, for example, 1600 R. P. M., the vacuum conditions have, during that time, changed from 8½ inches to 5 inches and the fuel quantity supplied to each cylinder has varied from 120 cubic millimeters (at 2400 R. P. M.) to substantially 148 cubic millimeters (at 1600 R. P. M.). Device 89, being an air-to-fuel ratio control, as distinguished from merely a governor, will maintain the fixed air-to-fuel ratio selected regardless of the speed or load conditions and regardless of the throttle positions.

The function of fuel ratio control device 89 is to maintain a selected air-to-fuel ratio at all times, regardless of any combinations of speed and load. This is done by adjusting the spring return of spring 100 (Figure 5). Adjusting retainer 106 inwardly of housing 90 causes a less and less number of convolutions of the spring to be effective in their operation in resisting the movement of diaphragm 92. The fewer the effective convolutions of spring 100, the greater the manifold pressure change required for a given motion of throttle rod 122.

Thus once the manifold pressure conditions and their air flow to the engine are known, adjustment of spring 100 can be made to maintain at all times the selected air-to-fuel ratio under all conditions of operation.

Referring now to the control modification illustrated in Figure 23, pump 128 is similar to that illustrated in Figure 2 and is provided with collector ring 138 adjustably secured as at 214 to control fingers 212 (Figure 2), it being understood that pump 296, with or without connections 292 (Figures 1 and 22) is used. In fact the only major change in this Figure 23 over Figure 1 is the control. Pump shaft 142 is provided, as already described, having operating cam 156 thereon for the pumping assemblies (Figure 2). Collector ring 138 is provided with pin 134 connected through ball 132 and slot 130 to pump throttle rod 122 slidably mounted in housing 126.

Rod 122 is pivotally connected as at 438 to link 440. Link 440 is adjustably connected through coupling 442 to link 444, set screws 446 and 448 securing links 440 and 444 to coupling 442. Link 444 is pivotally, adjustably and slid-

ably connected through the pin and slot connection 450 to throttle lever 452, similar to throttle lever 64.

5 Lever 452 is secured to shaft 454 of butterfly valve 456, said shaft being journalled in throttle housing 458, similar to housing 62. Shaft 454 is also adjustably secured as at 460 to lever 462 which is pivotally and adjustably connected as at 464 to a suitable link 466 adapted to be connected to and operated by the usual foot or hand feed mechanism.

10 It will be seen that by operating link 466 valve 456 is operated simultaneously and to the same extent as at collector ring 138, and consequently the pumping assemblies shown in Figure 2, and already described.

15 In adjusting this mechanism, adjustment is made at 446, 448, 450, 460 and 464. The ratio of fuel and air mass flow is adjusted for any engine 20 to an optimum, by said adjustments, and these adjustments are locked to maintain this optimum, so that thereafter there is a proper relative operation between throttle valve 456 and the pumping assemblies.

25 It is to be understood that this application is not to be limited by the exact embodiments of the device shown, which are merely by way of illustration and not limitation as various and other forms of the device will, of course, be apparent to those skilled in the art without departing from the spirit of the invention or the scope of the claims.

I claim:

35 1. A pumping device including a casing having pumping assemblies therein, a rotatable shaft having a cam thereon, each assembly comprising a reciprocating cam follower disposed in a cylindrical bore provided substantially equidistant from and radially of the axis of the shaft, said 40 follower being adapted to be reciprocated by said cam, a lower spring seat member disposed in said bore, an upper spring seat member engaging said cam follower a spring interposed between said spring seat members and urging said cam follower toward said cam, a flexible diaphragm disposed in said bore, a stop member disposed in said bore and fixing said diaphragm therein, said bore below said diaphragm having a wall forming a fuel cavity shaped to permit deflection of said diaphragm, said casing being provided with hydraulic fluid disposed therein above and to a predetermined level above said diaphragm, a barrel member fixed in said first named bore above said stop member and having a cylindrical barrel bore 45 therein, said barrel member having a port to permit said hydraulic fluid to flow into said barrel bore, said stop member having a passage connecting said barrel bore to the first named bore between the stop member and diaphragm, a plunger 50 mounted for reciprocation in said barrel bore, the end of said plunger in said barrel bore being cut away adjacent the ports in said barrel member whereby the position of said cut away portion controls the amount of hydraulic fluid disposed 55 between said plunger and diaphragm and consequently the amount of deflection of said diaphragm as said plunger moves toward said diaphragm, the other end of said plunger being connected to said upper spring seat member, a throttle yoke disposed between said lower spring seat and barrel member and slidably embracing said plunger, rotation of said yoke causing rotation of said plunger to selectively position said cut away portion of said plunger with respect to the barrel member port, an oscillatable finger mem-

ber for rotating said yoke, a collector member connected to each finger member of each pumping assembly for rotating each yoke, a fuel intake manifold communicating with the fuel cavity, an inlet valve between said manifold and cavity, an outlet from said cavity, and an outlet valve between said cavity and outlet.

2. A pumping device including a casing having a pumping assembly therein, a movable cam, said assembly comprising a reciprocating cam follower disposed in a cylindrical bore provided substantially equidistant from and radially of the axis of the shaft, said follower being adapted to be reciprocated by said cam, a lower spring seat member disposed in said bore, an upper spring seat member engaging said cam follower, a spring interposed between said spring seat members and urging said cam follower toward said cam, a flexible diaphragm disposed in said bore, a stop member disposed in said bore and fixing said diaphragm therein, said bore below said diaphragm having a wall forming a fuel cavity shaped to permit deflection of said diaphragm, said casing being provided with hydraulic fluid disposed therein above and to a predetermined level above said diaphragm, a barrel member fixed in said first named bore above said stop member and having a cylindrical barrel bore therein, said barrel member having a port to permit said hydraulic fluid to flow into said barrel bore, said stop member having a passage connecting said barrel bore to the first named bore between the stop member and diaphragm, a plunger mounted for reciprocation in said barrel bore, the end of said plunger in said barrel bore being cut away adjacent the ports in said barrel member whereby the position of said cut away portion controls the amount of hydraulic fluid disposed between said plunger and diaphragm and consequently the amount of deflection of said diaphragm as said plunger moves toward said diaphragm, the other end of said plunger being connected to said upper spring seat member, a throttle yoke disposed between said lower spring seat and barrel member and slidably embracing said plunger, rotation of said yoke causing rotation of said plunger to selectively position said cut away portion of said plunger with respect to the barrel member port, an oscillatable finger member for rotating said yoke, a means for oscillating said finger member, a fuel inlet communicating with said fuel cavity, an inlet valve between said fuel inlet and cavity, an outlet from said cavity, and an outlet valve between said cavity and outlet.

3. A pumping device including a casing having pumping assemblies therein, a rotatable shaft having a cam thereon, each assembly comprising a reciprocating cam follower disposed in a cylindrical bore provided substantially equidistant from and radially of the axis of the shaft, said follower being adapted to be reciprocated by said cam, a lower spring seat member disposed in said bore, an upper spring seat member engaging said cam follower, a spring interposed between said spring seat members and urging said cam follower toward said cam, a flexible diaphragm disposed in said bore, a stop member disposed in said bore and fixing said diaphragm therein, said bore below said diaphragm having a wall forming a fuel cavity shaped to permit deflection of said diaphragm, said casing being provided with hydraulic fluid disposed therein above and to a predetermined level above said diaphragm, a barrel member fixed in said first named bore above said stop member and

having a cylindrical barrel bore therein, said barrel member having a port to permit said hydraulic fluid to flow into said barrel bore, said stop member having a passage connecting said barrel bore to the first named bore between the stop member and diaphragm, a plunger mounted for reciprocation in said barrel bore, the end of said plunger in said barrel bore being cut away adjacent the ports in said barrel member whereby the position of said cut away portion controls the amount of hydraulic fluid disposed between said plunger and diaphragm and consequently the amount of deflection of said diaphragm as said plunger moves toward said diaphragm, the other end of said plunger being connected to said upper spring seat member, the connection between said plunger and upper spring seat including a head provided on said plunger disposed between said upper spring seat and cam follower and of less thickness than the space between said cam follower and upper spring seat whereby there is a small lost motion between said plunger and upper spring seat and cam follower, a throttle yoke disposed between said lower spring seat and barrel member and slidably embracing said plunger, rotation of said yoke causing rotation of said plunger to selectively position said cut away portion of said plunger with respect to the barrel member port, an oscillatable finger member for rotating said yoke, a collector member connected to each finger member of each pumping assembly for rotating each yoke, a fuel intake manifold communicating with the fuel cavity, an inlet valve between said manifold and cavity, an outlet from said cavity, and an outlet valve between said cavity and outlet.

4. A pumping device including a casing having a pumping assembly therein, a variable cam, said assembly comprising a reciprocating cam follower disposed in a cylindrical bore provided substantially equidistant from and radially of the axis of the shaft, said follower being adapted to be reciprocated by said cam, a lower spring seat member disposed in said bore, an upper spring seat member engaging said cam follower, a spring interposed between said spring seat members and urging said cam follower toward said cam, a flexible diaphragm disposed in said bore, a stop member disposed in said bore and fixing said diaphragm therein, said bore below said diaphragm having a wall forming a fuel cavity shaped to permit deflection of said diaphragm, said casing being provided with hydraulic fluid disposed therein above and to a predetermined level above said diaphragm, a barrel member fixed in said first named bore above said stop member and having a cylindrical barrel bore therein, said barrel member having a port to permit said hydraulic fluid to flow into said barrel bore, said stop member having a passage connecting said barrel bore to the first named bore between the stop member and diaphragm, a plunger mounted for reciprocation in said barrel bore, the end of said plunger in said barrel bore being cut away adjacent the ports in said barrel member whereby the position of said cut away portion controls the amount of hydraulic fluid disposed between said plunger and diaphragm and consequently the amount of deflection of said diaphragm as said plunger moves toward said diaphragm, the other end of said plunger being connected to said upper spring seat member, the connection between said plunger and upper spring seat including a head provided on said plunger disposed between said upper spring seat and cam follower and of less

thickness than the space between said cam follower and upper spring seat whereby there is a small lost motion between said plunger and upper spring seat and cam follower, a throttle yoke disposed between said lower spring seat and barrel member and slidably embracing said plunger, rotation of said yoke causing rotation of said plunger to selectively position said cut away portion of said plunger with respect to the barrel member port, an oscillatable finger member for rotating said yoke, means for oscillating said finger member, a fuel inlet communicating with said fuel cavity, an inlet valve between said fuel inlet and cavity, an outlet from said cavity, and an outlet valve between said cavity and outlet.

5. A pumping device including a casing having pumping assemblies therein, a rotatable shaft having a cam thereon, each assembly comprising a bore in said casing disposed substantially equidistant from and radially of the axis of said shaft, a flexible diaphragm disposed in said bore, a stop member disposed in said bore adjacent said diaphragm, said bore below said diaphragm having a wall forming a fuel cavity shaped to permit deflection of said diaphragm, said casing being provided with hydraulic fluid disposed therein above and to a predetermined level above said diaphragm, a barrel member fixed in said bore above said stop member and having a cylindrical barrel bore therein, said barrel member having a port to permit said hydraulic fluid to flow into said barrel bore, said stop member having a passage connecting said barrel bore to the first named bore between the stop member and diaphragm, a plunger mounted for reciprocation in said barrel bore, the end of said plunger in said barrel bore being cut away adjacent the port in said barrel member whereby the position of said cut away portion controls the amount of hydraulic fluid disposed between said plunger and diaphragm, and consequently the amount of deflection of said diaphragm as said plunger moves toward said diaphragm, the other end of said plunger being provided with means resiliently urging said plunger to follow said cam whereby said plunger is reciprocated in accordance with the movement of said cam, a throttle yoke slidably embracing said plunger, rotation of said yoke causing rotation of said plunger to selectively position the cut away portion of said plunger with respect to the barrel member port, an oscillatable finger member for rotating said yoke, a collector member connected to each finger member of each pumping assembly for rotating each yoke, a fuel intake manifold communicating with the fuel cavity, an inlet valve between said manifold and cavity, an outlet from said cavity, and an outlet valve between said cavity and outlet.

6. A pumping device including a casing having pumping assemblies therein, a cam movable in said casing, each assembly comprising a bore in said casing, a flexible diaphragm disposed in said bore, said bore below said diaphragm having a wall forming a fuel cavity shaped to permit deflection of said diaphragm, said casing being provided with hydraulic fluid disposed therein above and to a predetermined level above said diaphragm, a barrel member fixed in said bore above said diaphragm and having a cylindrical barrel bore therein, said barrel member having a port to permit said hydraulic fluid to flow into said barrel bore, said bore communicating with said first named bore above said diaphragm, a plunger mounted for reciprocation in said barrel bore, the

end of said plunger in said barrel bore being cut away adjacent the port in said barrel member whereby the position of said cut away portion controls the amount of hydraulic fluid disposed

5 between said plunger and diaphragm, and consequently the amount of deflection of said diaphragm as said plunger moves toward said diaphragm, the other end of said plunger being provided with means resiliently urging said plunger to follow said cam whereby said plunger is reciprocated in accordance with the movement of said cam, means for rotating said plunger, a collector member connected to each of said last named means of each pumping assembly for rotating each plunger, a fuel inlet communicating with the fuel cavity, an inlet valve between said inlet and cavity, an outlet from said cavity, and an outlet valve between said cavity and outlet.

7. A pumping device including a casing having

20 pumping assemblies therein, a cam movable in said casing, each assembly comprising a bore in said casing, a flexible diaphragm disposed in said bore, said bore below said diaphragm having a wall forming a fuel cavity shaped to permit deflection of said diaphragm, said casing being provided with hydraulic fluid disposed therein above and to a predetermined level above said diaphragm, a barrel member fixed in said bore above

25 said diaphragm, and having a cylindrical barrel bore therein, said barrel member having a port to permit said hydraulic fluid to flow into said barrel bore, said barrel bore communicating with the first named bore above said diaphragm, a plunger having an end mounted for reciprocation in

30 said barrel bore, the other end of said plunger being provided with means resiliently urging said plunger to follow said cam whereby said plunger is reciprocated by said cam, means for moving said plunger whereby said plunger controls the

35 port to vary the amount of hydraulic fluid disposed between said plunger and diaphragm, and consequently the amount of deflection of said diaphragm as said plunger moves toward said diaphragm, a collector member connected to each of

40 said last named means of each pumping assembly for controlling each of said last named means, a fuel inlet communicating with the fuel cavity, an inlet valve between said inlet and cavity, an outlet from said cavity, and an outlet valve between said cavity and outlet.

8. A pumping device including a casing having a pumping assembly therein, a movable cam, said assembly comprising a bore in said casing, a flexible diaphragm disposed in said bore, said bore

55 below said diaphragm having a wall forming a fuel cavity shaped to permit deflection of said diaphragm, said casing being provided with hydraulic fluid disposed therein above and to a predetermined level above said diaphragm, a barrel

60 member fixed in said bore above said diaphragm and having a cylindrical barrel bore therein, said barrel member having a port to permit said hydraulic fluid to flow into said barrel bore, said barrel bore communicating with the first named bore above said diaphragm, a plunger mounted for reciprocation in said barrel bore, the end of

65 said plunger in said barrel bore being cut away adjacent the port in said barrel member whereby the position of said cut away portion controls the amount of hydraulic fluid disposed between said plunger and diaphragm, and consequently the amount of deflection of said diaphragm as said plunger moves toward said diaphragm, the other end of said plunger being provided with

70 means resiliently urging said plunger to follow

said cam whereby said plunger is reciprocated in accordance with the movement of said cam, means for rotating said plunger, a fuel inlet communicating with said fuel cavity, an inlet valve between said fuel inlet and cavity, an outlet from said cavity, and an outlet valve between said cavity and outlet.

9. A pumping device including a casing having a pumping assembly therein, a movable cam, said assembly comprising a bore in said casing, a flexible diaphragm disposed in said bore, said bore below said diaphragm having a wall forming a fuel cavity shaped to permit deflection of said diaphragm, said casing being provided with hydraulic fluid disposed therein above and to a predetermined level above said diaphragm, a barrel member fixed in said bore above said diaphragm and having a cylindrical barrel bore therein, said barrel member having a port to permit said hydraulic fluid to flow into said barrel bore, said barrel bore communicating with the first named bore above said diaphragm, a plunger having an end mounted for reciprocation in said barrel bore, the other end of said plunger being provided with means resiliently urging said plunger to follow said cam whereby said plunger is reciprocated by said cam, means for moving said plunger whereby said plunger controls the port to vary the amount of hydraulic fluid disposed between said plunger and diaphragm, and consequently the amount of deflection of said diaphragm as said plunger moves toward said diaphragm, a fuel inlet communicating with said fuel cavity, an inlet valve between said fuel inlet and cavity, an outlet from said cavity, and an outlet valve between said cavity and outlet.

10. A pumping device including a casing having pumping assemblies therein, a cam movable in said casing, each assembly comprising a bore in said casing, a flexible diaphragm disposed in said bore, said bore below said diaphragm having a wall forming a fuel cavity shaped to permit deflection of said diaphragm, said casing being provided with hydraulic fluid disposed therein above and to a predetermined level above said diaphragm, a barrel member fixed in said bore above said diaphragm and having a cylindrical barrel bore therein, said barrel member having a port to permit said hydraulic fluid to flow into said barrel bore, said barrel bore communicating with the first named bore above said diaphragm, a plunger having an end mounted for reciprocation in said barrel bore, the other end of said plunger being actuated by the cam whereby the plunger is reciprocated by said cam, means operable to cause the plunger to selectively variably control said port to vary the amount of hydraulic fluid disposed between said plunger and diaphragm, and consequently the amount of deflection of said diaphragm as said plunger moves toward said diaphragm, a fuel inlet communicating with said fuel cavity, an inlet valve between said fuel inlet and cavity, an outlet from said cavity, and an outlet valve between said cavity and outlet.

11. A pumping device including a casing having pumping assemblies therein, a cam movable in said casing, each assembly comprising a bore in said casing, a flexible diaphragm disposed in said bore, said bore below said diaphragm having a wall forming a fuel cavity shaped to permit deflection of said diaphragm, said casing being provided with hydraulic fluid disposed therein above and to a predetermined level above said diaphragm, a barrel member fixed in said bore

above said diaphragm and having a cylindrical barrel bore therein, said barrel member having a port to permit said hydraulic fluid to flow into said barrel bore, said barrel bore communicating with the first named bore above said diaphragm, a plunger having an end mounted for reciprocation in said barrel bore, the other end of said plunger being actuated by the cam whereby the plunger is reciprocated by said cam, means operable to cause the plunger to selectively variably control said port to vary the amount of hydraulic fluid disposed between said plunger and diaphragm, and consequently the amount of deflection of said diaphragm as said plunger moves toward said diaphragm, a collector member connected to each of said last named means of each pumping assembly for controlling each of said last named means, a fuel inlet communicating with the fuel cavity, an inlet valve between said inlet cavity, an outlet from said cavity, and an outlet valve between said cavity and outlet.

12. A pumping device including a casing having pumping assemblies therein, a cam movable in said casing, each assembly comprising a bore in said casing, a flexible diaphragm disposed in said bore, said bore below said diaphragm having a wall forming a fuel cavity shaped to permit deflection of said diaphragm, said casing above said diaphragm being adapted to be provided with a predetermined amount of hydraulic fluid, a barrel member fixed in said bore above said diaphragm and having a cylindrical barrel bore therein, said barrel member having a port to permit said hydraulic fluid to flow into said barrel bore, said barrel bore communicating with the first named bore above said diaphragm, a plunger having an end mounted for reciprocation in said barrel bore, the other end of said plunger being actuated by the cam whereby the plunger is reciprocated by said cam, means operable to cause the plunger to selectively variably control said port to vary the amount of hydraulic fluid disposed between said plunger and diaphragm, and consequently the amount of deflection of said diaphragm as said plunger moves toward said diaphragm, a fuel inlet communicating with said fuel cavity, and inlet valve between said fuel inlet and cavity, an outlet from said cavity, and an outlet valve between said cavity and outlet.

13. A pumping device including a casing having a pumping assembly therein, a movable cam, said assembly comprising a bore in said casing, a flexible diaphragm disposed in said bore, said bore below said diaphragm having a wall forming a fuel cavity shaped to permit deflection of said diaphragm, said casing above said diaphragm being adapted to be provided with a predetermined amount of hydraulic fluid, a barrel member fixed in said bore above said diaphragm and having a cylindrical barrel bore therein, said barrel member having a port to permit said hydraulic fluid to flow into said barrel bore, said barrel bore communicating with the first named bore above said diaphragm, a plunger having an end mounted for reciprocation in said barrel bore, the other end of said plunger being actuated by the cam whereby the plunger is reciprocated by said cam, means operable to cause the plunger to selectively variably control said port to vary the amount of hydraulic fluid disposed between said plunger and diaphragm, and consequently the amount of deflection of said diaphragm as said plunger moves toward said diaphragm, a fuel inlet communicating with said fuel cavity, an inlet valve between said fuel inlet and cavity, an

outlet from said cavity, and an outlet valve between said cavity and outlet.

14. In a pump, the combination of a casing having an upper housing and a depending housing, a rotatable cam shaft in said upper housing, a cam operable for a portion of the rotation of said shaft, a bell crank pivoted in said upper housing adjacent said cam and adapted to be oscillated thereby, said bell crank being operable a predetermined amount by said cam for a predetermined time, said depending housing having a cylindrical bore therein, a flexible diaphragm disposed in said bore, a stop member disposed above and fixing said diaphragm in said bore, said stop member having a passage connecting the bore above the stop member to the bore between the stop member and diaphragm, a piston mounted for reciprocation in said bore above the stop member, said casing having a passage connecting the bore above and below the piston, said piston being adapted to close communication between the bore and passage at a predetermined point in its travel, a connection between the bell crank and piston whereby the bell crank is adapted to raise the piston its maximum distance from the diaphragm by operation of said bell crank by said cam, resilient means for moving said piston toward said diaphragm when said bell crank is free from operation by said cam, said lower housing having a wall below the diaphragm forming a fuel cavity adapted to be filled when the diaphragm causes vacuum conditions in said cavity by returning from deflected position, an inlet to said cavity, an inlet valve between said inlet and cavity, an outlet from said cavity, and an outlet valve between said cavity and outlet.

15. In a pump, the combination of a casing having housing portions, a rotatable cam shaft in one of said housing portions, a cam operable for a portion of the rotation of said shaft, a bell crank pivoted in said first named housing portion adjacent said cam and adapted to be oscillated thereby, said other housing portion having a cylindrical bore therein, a flexible diaphragm disposed in said bore, a piston mounted for reciprocation in said bore on one side of said diaphragm, said casing having a passage connecting the bore above and below the piston, said piston being adapted to close communication between the bore and passage at a predetermined point in its travel, said casing being adapted to have a predetermined amount of hydraulic fluid therein on said one side of said diaphragm, a connection between the bell crank and piston whereby the bell crank is adapted to raise the piston its maximum distance from the diaphragm by operation of the cam shaft on said bell crank thereby permitting a predetermined amount of hydraulic fluid to be disposed between said piston and diaphragm, resilient means for moving said piston toward said diaphragm when said bell crank is free from operation by said cam to thereby cause said hydraulic fluid to deflect said diaphragm, said other housing portion having a wall disposed on the other side of said diaphragm forming a fuel cavity adapted to be filled on the suction stroke when the diaphragm returns from its deflected position, an inlet to said cavity, an inlet valve between said inlet and cavity, an outlet from said cavity, and an outlet valve between said cavity and outlet, the amount of fuel dispensed from the cavity determining the stroke of the piston.

16. In a pump, the combination of a casing having housings, a rotatable cam shaft in one of

said housings, a cam operable for a portion of the rotation of said shaft, a bell crank pivoted in said first named housing adjacent said cam and adapted to be oscillated thereby, said other housing having a cylindrical bore therein, a flexible diaphragm disposed in said bore, a piston mounted for reciprocation in said bore above said diaphragm, said casing having a passage connecting the bore above and below the piston, said piston being adapted to close communication between the bore and passage at a predetermined point in its travel, said casing being adapted to have a predetermined amount of hydraulic fluid therein above said diaphragm, a loose connection between the bell crank and piston whereby the bell crank is adapted to raise the piston its maximum distance from the diaphragm by operation of the cam on said bell crank, the bell crank returning to its position where the piston has completed its stroke independently of the piston, resilient means for moving said piston toward said diaphragm when said bell crank is free from operation by said cam to thereby cause said hydraulic fluid to deflect said diaphragm, said lower housing having a wall below the diaphragm forming a fuel cavity adapted to be filled when the diaphragm causes vacuum conditions in said cavity by returning from deflected position, an inlet to said cavity, an inlet valve between said inlet and cavity, an outlet from said cavity, and an outlet valve between said cavity and outlet, the amount of fuel dispensed from the cavity determining the stroke of the piston.

17. In a pump, the combination of a casing having housings, a rotatable cam shaft in one of said housings, cams operable for a portion of the rotation of said shaft, said cams being set in overlapping relation to each other whereby when one cam is operative the other cam is inoperative, a bell crank pivoted in said first named housing adjacent each of said cams and adapted to be operated by the respective cams, said other housing having cylindrical bores therein, a flexible diaphragm disposed in each of said bores, a piston mounted for reciprocation in each of said bores above the diaphragms disposed therein, said casing having a passage connecting each bore above and below the piston therein, each piston being adapted to close communication between its bore and the associated passage at a predetermined point in the travel of the piston, said casing being adapted to have a predetermined amount of hydraulic fluid therein above said diaphragms, a loose connection between the bell cranks and the associated piston whereby each bell crank is adapted to raise its piston the maximum travel thereon from the associated diaphragm by operation of the associated cam on said bell crank, each bell crank returning to its position where the associated piston has completed its stroke independently of its piston, resilient means for moving each piston toward its diaphragm when its bell crank is free from operation by its cam to thereby cause said hydraulic fluid to deflect said diaphragms, said lower housing having a wall below each diaphragm forming a fuel cavity adapted to be filled when the diaphragms cause vacuum conditions in said cavities by returning from deflected position, an inlet to each cavity, an inlet valve between each inlet and cavity, an outlet from each cavity, and an outlet valve between each cavity and outlet, the amount of fuel dispensed from each cavity determining the stroke of each piston.

18. A control for a device of the character described comprising a housing, a diaphragm disposed in said housing forming separated chambers therein, one of said chambers being vented, the other of said chambers being adapted to be connected to means for subjecting said second named chamber to pressure (or vacuum) conditions, a throttle rod housing adjacent the first named chamber, a throttle rod movably mounted in said throttle rod housing, an adjustable nut in said first named chamber connecting said throttle rod to said diaphragm, an adjustable spring retainer threadedly mounted in said second named chamber and provided with spring receiving convolutions in the second named chamber, said retainer having a portion extending outwardly of said housing whereby said retainer may be rotated, means for capping the outwardly extending portion of said retainer and for sealing said second named chamber, a spring seat on said diaphragm and a spring secured at one end to said seat on said diaphragm and having convolutions engaging in the convolutions of said spring retainer, rotation of said spring retainer adjusting the number of convolutions of the spring disposed in the convolutions of said retainer.

19. A control for a device of the character described comprising a housing, a diaphragm disposed in said housing forming separated chambers therein, one of said chambers being vented, the other of said chambers being adapted to be connected to means for subjecting said second named chamber to pressure (or vacuum) conditions, a throttle rod housing connected to the first named housing adjacent the one of said chambers, a throttle rod slidably mounted in said throttle rod housing, an adjustable nut in one of said chambers connecting said throttle rod to said diaphragm, an adjustable spring retainer threadedly mounted in one of said chambers and disposed with convolutions in the last named housing, said retainer having a portion extending outwardly of said housing whereby said retainer may be rotated, means for capping the outwardly extending end of said retainer and for sealing said last named chamber, a spring seat on said diaphragm and a spring secured at one end to said seat on said diaphragm and having convolutions engaging in the convolutions of said spring retainer, rotation of said spring retainer adjusting the number of convolutions of the spring disposed in the convolutions of said retainer.

20. A pumping device including a casing having a pumping assembly therein, a movable cam, said assembly comprising a fluid retaining cavity in said casing, a flexible diaphragm mounted in said casing, said casing on one side of said diaphragm having a wall forming a fuel cavity shaped to permit deflection of said diaphragm, said casing on the other side of said diaphragm being adapted to be provided with a predetermined amount of hydraulic fluid in said fluid retaining cavity, said casing being provided with a barrel bore on said other side of and in communication with said diaphragm, at least one port providing communication for said hydraulic fluid between said barrel bore and said fluid retaining cavity, a plunger having an end mounted

5 for reciprocation in said barrel bore, the other end of said plunger being actuated by said cam whereby the plunger is reciprocated by said cam, means operable to cause the plunger to selectively variably control said port to vary the amount of hydraulic fluid disposed between said plunger and diaphragm, and consequently the amount of deflection of said diaphragm during a pumping stroke, a fuel inlet communicating with said fuel cavity, an inlet valve between said fuel inlet and fuel cavity, an outlet from said fuel cavity, and an outlet valve between said fuel cavity and outlet.

21. In a system of the character described, the combination of a driven pump delivering a metered output at predetermined intervals, a pneumatic control device including a spring pressed movable diaphragm connected to said pump for determining the amount of output, means for controlling the number of effective convolutions of said spring in actuating said diaphragm, a pneumatic connection between said diaphragm and a means for subjecting said diaphragm to pressure conditions on said spring pressed side thereof for varying the output of said pump, said pump including a casing having a pumping assembly therein, a movable cam, said assembly comprising a fluid retaining cavity in said casing, a flexible diaphragm mounted in said casing, said casing on one side of said diaphragm having a wall forming a fluid cavity shaped to permit deflection of said diaphragm, said casing on the other side of said diaphragm being adapted to be provided with a predetermined amount of hydraulic fluid in said fluid retaining cavity, said casing being provided with a barrel bore on said other side of and in communication with said diaphragm, at least one port providing communication for said hydraulic fluid between said barrel bore and said fluid retaining cavity, a plunger having an end mounted for reciprocation in said barrel bore, the other end of said plunger being actuated by said cam whereby the plunger is reciprocated by said cam, means operated by said control device to cause the plunger to selectively variably control said port to vary the amount of hydraulic fluid disposed between said plunger and diaphragm, and consequently the amount of deflection of said diaphragm during a pumping stroke, a fluid inlet communicating with said fluid cavity and being connected to a fluid supply, an inlet valve between said fluid inlet and fluid cavity, an outlet from said cavity, and an outlet valve between 55 said fluid cavity and outlet.

WILLIAM H. MASHINTER.
